UNITED STATES PATENT OFFICE.

HARRY E. DOERR, OF ST. LOUIS, MISSOURI, ASSIGNOR TO SCULLIN-GALLAGHER IRON & STEEL COMPANY, OF ST. LOUIS, MISSOURI, A CORPORATION OF MISSOURI.

RAILWAY-CAR TRUCK.

1,097,968.

Specification of Letters Patent. Patented May 26, 1914.

Application filed October 27, 1913. Serial No. 797,566.

To all whom it may concern:

Be it known that I, HARRY E. DOERR, a citizen of the United States, residing at St. Louis, Missouri, have invented a certain new and useful Improvement in Railway-Car Trucks, of which the following is a full, clear, and exact description, such as will enable others skilled in the art to which it appertains to make and use the same.

10 This invention relates to railway car trucks, and has for its main object to provide a freight car truck in which the journal-boxes are snugly held in operative position in the side frames, and which can be readily 15 and easily removed therefrom or inserted therein.

Another object is to provide a freight car truck having cast metal side frames that co-operate with standard Master Car Builders' 20 journal-boxes in such a manner as to hold the box firmly in operative position therein without the use of the usual through-bolts on each side of said box.

Other objects and desirable features of 25 my invention will be hereinafter pointed out.

Figure 1 of the drawings is a side elevational view of a portion of a car truck constructed in accordance with my invention, the journal-box being shown in vertical section; Fig. 2 is an end elevational view of the parts shown in Fig. 1; Fig. 3 is a horizontal sectional view taken on the line 3—3 of Fig. 30 1; and Fig. 4 is a side elevational view illustrating a slight modification of my invention.

Referring to Figs. 1 to 3 of the drawings which illustrate the preferred form of my invention, A designates the cast metal side frame of a car truck, and B designates a 40 standard Master Car Builders' journal-box that co-operates with said frame. Means is provided for removably securing said journal-box in operative position in the side frame, and in the embodiment of my invention herein shown said means comprises an L-shaped member or strap C that engages the bottom and one side wall of the journal-box and is removably secured to the frame A by means of suitable fastening devices 1 that pass through the bifurcated ends of 45 said strap and through integral ears 2 on said frame. The side frame A is provided with integral portions that engage the top and opposite side wall of the journal-box 50 and co-operate with the strap C to securely 55

hold the box in operative position and prevent any movement thereof in a vertical or horizontal direction with respect to said frame. The means that I prefer to use to prevent transverse movement of the journal-box with respect to the frame consists of vertically disposed ribs 3 formed on the portions of the frame A and the strap C that engage the side wall of the journal-box, and which lie in the usual vertically disposed 60 grooves 4 in the side walls of the journal-box, as shown clearly in Fig. 3. In order to prevent any tendency of the box to rock when in position in the frame I provide an abutment 5 on the frame A and a similar 65 abutment 6 on the strap B that engage the usual lugs 7 on the upper side walls of the journal-box. In the preferred form of my invention the strap C is held in position by means of the fastening devices 1 at each end 70 thereof whereby the strap may be swung in the direction indicated by the arrows when the lowermost fastening device is removed so as to permit of the removal or insertion 75 of a journal-box or it may be detached from the frame by removing the other fastening device.

In Fig. 4 I have illustrated a slight modification of my invention in which I form an integral horizontal pin 8 in the bifurcated 80 upper end of the strap C' that co-operates with a hook-shaped portion 9 formed integral with the side frame A'. By constructing the truck in this manner I am enabled to detach the strap C' from the frame 85 A' by simply removing the single fastening device and swinging the strap about the pin 8 as a pivot until it can be lifted bodily out of the hooked portion 9.

From the foregoing it will be seen that I 90 have provided a truck in which a standard Master Car Builders' journal-box is normally held in snug engagement with a cast metal side frame in such a manner as to prevent any tendency of said box to rock or to 95 move in any direction out of its normal position with respect to said frame.

A truck of the character herein described is composed of few, simple parts that cannot get out of order easily and can be produced at a low cost of manufacture.

Having thus described my invention, what I claim as new and desire to secure by Letters Patent is:

1. In a car truck, a journal-box provided

with the usual continuous vertical grooves in the side walls thereof, laterally extending lugs at the upper and lower ends of said grooves, a side frame, and means coöperating with the portion of said grooves intermediate said lugs only for preventing transverse movement of said box with respect to said frame.

2. In a car truck, a journal-box provided with vertical grooves in the side walls thereof, laterally extending lugs on said box adjacent the upper and lower ends of said grooves, a side frame provided with an integral portion that coöperates with the groove formed in one side wall of said journal-box intermediate the lugs on that side, and a member detachably connected to said side frame and provided with a portion that coöperates with the intermediate portion only of the groove in the opposite side wall of said box.

3. In a car truck, a standard Master Car Builders' journal-box, a cast metal side frame provided with integral portions that engage the top and central portion only of one side wall of the journal-box, and a member detachably connected to said side frame that engages the bottom and the central portion only of the opposite side wall of said box.

4. In a car truck, a journal-box provided with laterally extending lugs adjacent the upper and lower edges of the side walls thereof, a cast metal side frame provided with means for engaging the side walls of said journal-box intermediate said lugs, and

abutments on said side frame that engage the side edges of said lugs.

5. In a car truck, a journal-box provided with laterally projecting lugs adjacent the upper and lower edges of the side walls thereof, a cast metal side frame, means on said frame for engaging the top and one side wall of said box, a strap that engages the bottom of said box and the opposite side wall intermediate said lugs, and means for securing said strap to said side frame.

6. In a car truck, a cast metal side frame having integral portions that form the top and one side of a substantially rectangular opening to receive the journal-box, a member that forms the opposite side and bottom of said opening, and means comprising a hook-shaped portion on said frame and a co-operating pin on said member whereby said member is removably secured to said frame.

7. In a car truck, a journal-box provided with vertically disposed grooves in the side walls thereof, laterally projecting lugs adjacent the upper and lower edges of said side walls, and a cast metal side frame provided with ribs that coöperate with said grooves intermediate said lugs so as to hold said box in operative position in said frame.

In testimony whereof I hereunto affix my signature in the presence of two witnesses, this 21st day of October 1913.

HARRY E. DOERR.
